(57) CLAIM

(21) Appl. No.: 29/125,060

The ornamental design for a hand held hair dryer attachment for dogs with means for securing to a wall, as shown and described.

(22) Filed: Jun. 19, 2000

DESCRIPTION

(51) LOC (7) Cl. 28-03

The claimed hand held hair dryer attachment for dogs with means for securing to a wall is used for efficiently and safely drying a dog's fur.

(52) U.S. Cl. D28/12; D28/16

FIG. 1 is a left side elevational view of a hand held hair dryer attachment for dogs with means for securing to a wall showing my new design, the broken line showing of the dog, hair dryer, and wall with hook is for illustrative purposes only and forms no part of the claimed design;
